(57) **CLAIM**

The ornamental design of a hitch receiver trim cover, as shown and described.

DESCRIPTION

FIG. 1 is a perspective view of the hitch receiver trim cover of the present invention;

FIG. 2 is a rear elevational view thereof;

FIG. 3 is a right side elevational view thereof, the left side elevational view being a substantial mirror image thereof;

FIG. 4 is a bottom plan view thereof; and,

FIG. 5 is a top plan view thereof.
